(57) **CLAIM**

I claim the ornamental design for an L-shaped motor enclosure, as shown and described.

DESCRIPTION

FIG. 1 discloses the front view of the L-shaped motor enclosure

FIG. 2 discloses the back view of the L-shaped motor enclosure

FIG. 3 discloses the top view of the L-shaped motor enclosure

FIG. 4 discloses the front bottom view of the L-shaped motor enclosure

FIG. 5 discloses the right side view of the L-shaped motor enclosure

FIG. 6 discloses the left side view of the L-shaped motor enclosure; and,

FIG. 7 discloses the perspective view of the L-shaped motor enclosure.
